UNITED STATES PATENT OFFICE.

EDWARD H. ELLISON, OF JAMESTOWN, NEW YORK, ASSIGNOR TO MONARCH REFILLABLE FUSE CO., OF JAMESTOWN, NEW YORK, A CORPORATION OF NEW YORK.

ELECTRIC FUSE.

1,391,534.

Specification of Letters Patent. Patented Sept. 20, 1921.

Application filed January 2, 1919. Serial No. 269,187.

To all whom it may concern:

Be it known that I, EDWARD H. ELLISON, a citizen of the United States, residing at Jamestown, in the county of Chautauqua, State of New York, have invented certain new and useful Improvements in Electric Fuses, of which the following is a description, reference being had to the accompanying drawing and to the figures of reference marked thereon.

My invention relates to new and useful improvements in electric fuses.

The object of the invention is to provide an electric fuse in which the two knife blades and the fusible link are rigidly supported within an inclosing case so that the same may be readily removed and a new link placed therein when the same has been fused by an overcharge of electricity. At the same time I provide means whereby the knife blades may be readily inserted in the inclosing case after the renewal of the fusible link and in which it is impossible to change the relative alined position of the two knife blades, so that the fusible link can not be twisted in screwing up the ferrules or caps.

A further object of the invention is to provide a fuse of this character in which the connection between the knife blades and the link is made when removed from the core, so that it can be seen that a perfect electrical connection is made and at the same time a fuse is provided of few parts which may be readily interchanged.

A still further object of the invention is to provide an air tight inclosing tube in which the flames are confined upon the fusing of the link, and at the same time provide a simple, cheap and effective fuse having certain details of structure and combination of parts hereinafter more fully described.

In the accompanying drawings—

Figure 1 is a longitudinal sectional view of my improved fuse;

Fig. 2 is a side elevation, partly in section, taken at right angles to Fig. 1;

Fig. 3 is a perspective view of one knife blade and link showing the bridge pieces and washers in their separated relation;

Fig. 4 is a transverse sectional view taken on the line 4—4 Fig. 2.

Referring now to the drawings, 1 represents a cylindrical fiber inclosing case of the usual construction, having its ends exten-

nally screw-threaded, as indicated at 2 and 3, and upon which the ferrules or closing caps 4 and 5 are screwed, as will be later described. The knife blades 6 and 7, forming the electrical connection in the fuse box are of an elongated flat form and having their inner ends provided with openings 8, through which the bolts 9 and 10 pass and by means of which the fusible links 11 are connected thereto. The nuts 12 securely lock the fusible link to the knife blade and in order to form a better electrical connection, I employ the washers 13, as clearly shown in Figs. 1 and 2.

The knife blades 6 and 7, out beyond the openings 8, have the metal thereof struck up and down, as shown in Fig. 2, forming the oppositely extending lugs 14 and 15, which serve as stops for the bridge pieces, as will be later described. Beyond the lugs 14 and 15, the edges of the blades are provided with oppositely arranged notches 16 and 17, into which fit the bridge pieces 18 and 18'. These bridge pieces are made exactly alike, and are provided with a slot 19, forming a long arm 20 and a short arm 21, whereby the meeting edges of the same with the short and long arms of the opposing bridge piece, will come opposite the lugs 14 and 15, as clearly shown in Fig. 4 of the drawings.

The fiber washer 22 has an opening 23 to snugly fit the knife blade and the metal washer 24 has an opening 25 closely fitting the knife blade, as fully shown in the drawings. The washer 24 compresses the washer 22 against the end of the casing and forms a tight joint to prevent the flames from passing from the casing upon the fusing of the link.

From the foregoing description, it will be seen that the bridge pieces at one end are assembled so that their abutting ends come opposite the lugs 14 and 15, and rest in the notches 16 and 17, as clearly shown in Figs. 2 and 4 of the drawings, and the washer placed thereon and the knife blades inserted within the casing. When in this position the ends of the bridge pieces enter notches 26 in the ends of the casing and prevent the rotation of the knife blades in the casing, and the ferrule is then screwed upon the casing locking the parts in said position. The bridge pieces at the opposite end of the casing are then inserted and the two washers

slipped over the knife blade and the ferrule applied in the same manner as heretofore described.

Having thus described my invention, what 5 I claim as new and desire to secure by Letters Patent, is:

1. A fuse of the character described comprising an insulating casing, two knife blades, a removable fusible link connecting 10 said blades, said knife blades having notches in the opposing edges thereof and separate, integral lugs projecting from the opposite faces thereof, a two part bridge straddling said knife blades, each part adapted to abut

15 each of said lugs and to engage one of the notches in said blades, and means for closing the ends of the casing.

2. A fuse of the character described comprising an insulating casing having locking 20 notches, means for closing the ends thereof, two knife blades having continuous flat faces passing through said means, a removable fusible link connecting said blades, the opposing edges of said blades having notches 25 therein to form abutment shoulders and the faces of said blades being formed with reversely extending lugs, means engaging said lugs, shoulders on the blades and said notches in said casing, whereby to lock said blades 30 from rotation.

3. A fuse of the character described comprising an insulating casing having locking notches, means for closing the ends of said casing, two knife blades adapted to pass 35 therethrough, a removable fusible link connecting said blades, said blades being formed with notches in the edges and having oppositely extending lugs projecting from the flat faces thereof, bridge members engaging 40 the edge notches and said lugs on each face of the blades and the notches in said casing to non-rotatably lock said blades in said casing.

4. A fuse of the character described comprising an insulating casing, two knife blades, a removable fusible link connecting

said blades, a laterally movable two piece bridge straddling the knife blades and entering notches therein and having their outer ends resting in notches in the casing, lugs 50 struck up from the metal of the knife blades and arranged opposite the abutting ends of the bridge pieces to limit the inward movement thereof, a fiber washer longitudinally movable on the knife blade, a metal washer 55 longitudinally movable on the knife blades, and a ferrule screwed on the casing and adapted to force the washers up against the bridge pieces and lock the same in their interlocked positions. 60

5. A fuse of the character described comprising an insulating casing, two knife blades, a removable fusible link connecting the knife blades, laterally movable two piece bridge pieces having arms of different 65 lengths straddling the knife blades and entering notches in the casing, and the short arm of one piece abutting the long arm of the other piece, means for limiting the inward movement of said bridge pieces, and 70 a ferrule on the casing for locking the bridge pieces against outward movement in their interlocked position.

6. A fuse of the character described comprising an insulating casing, two knife 75 blades, a removable fusible link connecting said blades, said knife blades having notches in their opposing edges and separate lugs projecting from the opposite faces of the blades, said lugs being formed by 80 suitably slotting said blades and bending the metal thereof transversely to each face of a blade, a two-part bridge straddling said blades and held in position by engaging said locking notches and said lugs, and means for 85 closing the ends of the casing.

In testimony whereof, I affix my signature, in the presence of two witnesses.

EDWARD H. ELLISON.
